UNITED STATES PATENT OFFICE.

ROBERT K. DAWSON, OF AKRON, NEW YORK.

CHAIR BASE.

Application filed April 7, 1924. Serial No. 704,625.

To all whom it may concern:

Be it known that I, ROBERT K. DAWSON, a subject of the King of Great Britain, residing at Akron, in the county of Erie and State of New York, have invented a new and useful Improvement in Chair Bases, of which the following is a specification.

This invention relates to chair irons and more particularly to those parts of chair irons which support the chair seat from the upper end of the usual spindle or screw stem.

The objects of this invention are to improve and simplify the construction of chair irons and to reduce the weight thereof; also to provide a construction of this kind in which the usual squeaks to which chair irons have heretofore been subject are eliminated; also to provide an improved spring construction for opposing the swinging of the seat about the upper end of the spindle; also to provide improved means for adjusting the tension of the springs which hold the chair seat normally in their horizontal position; also to provide improved means for limiting the tilting movement of the chair seat relatively to the spindle, and also to improve the construction of devices of this kind in the other respects hereinafter specified.

In the accompanying drawings:

Fig. 1 is a top plan view of a chair iron embodying this invention.

Fig. 2 is a longitudinal, central, sectional side elevation thereof showing a chair seat mounted thereon.

Fig. 3 is a transverse sectional elevation thereof on line 3—3, Fig. 1.

Fig. 4 is a fragmentary sectional plan view thereof on an enlarged scale on line 4—4, Fig. 2.

Fig. 5 is a fragmentary longitudinal sectional elevation thereof on line 5—5, Fig. 3.

Fig. 6 is a fragmentary section thereof on line 6—6, Fig. 7.

Fig. 7 is a fragmentary transverse sectional elevation thereof on line 7—7, Fig. 2.

A, Fig. 2 represents the usual seat of a chair and B the spindle or upright adjusting screw, the lower end of which may be swivelled in the usual chair base, not shown. The chair seat is supported by means of the usual spider, which in the construction shown, comprises a pair of bars C, of angle-shaped cross section, the opposite ends of which are secured to the chair seat, and the

intermediate portions of which are depressed so as to extend slightly below the lower face of the chair seat. The two angle bars C are suitably connected, for example, by means of a plate D, which, in the construction shown, is secured to the intermediate portions of the angle bars by means of rivets d d' connecting the plate D with the upper or horizontal flanges of the angle bars C.

The spider may be supported from the chair spindle in any suitable manner, for example by means of a U-shaped bracket member E, the upwardly extending flanges or legs of which, in the construction shown, extend inside of the downwardly extending flanges of the angle bars C of the chair spider. A smaller U-shaped member F is arranged within the member E with its legs or flanges extending downwardly, and is secured thereto by means of rivets f passing through the flanges or legs of the two U-shaped members. These two members thus connected are provided in their horizontal portions with aligned holes through which the reduced upper end b of the spindle B extends, the U-shaped member E engaging the shoulder formed at the junction of the reduced portion b with the larger portion of the chair spindle B, and the upper end of the reduced portion b of the spindle is riveted or turned over against the upper face of the inverted U-shaped member F. By means of this construction the U-shaped member E is rigidly secured to the spindle B. The upwardly extending legs of the U-shaped member E are pivotally connected to the downwardly extending flanges of the bars C of the spider by means of a pivot bolt G. Other connecting means between the chair spindle and spider may be used if desired.

In chair irons as heretofore made it was customary to use one or more coil springs which were either subjected to compression or tension when the chair seat was tilted or swung rearwardly, and springs of this kind required a follower block or member which had to be guided in its lengthwise movement on the chair iron. This construction has the disadvantage, in the first place, that the tension or compression springs must be arranged at a distance from the pivot in order to obtain the necessary leverage to resist the tilting of the chair seat, which necessitated a cumbersome and heavy construction, and in the second place, the use of a follower or

lock engaging one end of the spring and movable relatively to the chair iron develops squeaks or other objectionable noises which are extremely difficult to eliminate.

5 In order to overcome these objections, one or more torsion springs H is provided in the construction illustrated, having intermediate looped portions h which are preferably arranged about the pivot bolt G. The rear 10 ends h' of the springs in the construction shown are arranged to press upwardly against the seat spider in rear of the pivot thereof, and the front ends h² of the springs extend forwardly and are adapted to be engaged by some means for adjusting the tension of the springs. In the construction shown for this purpose, the front ends of the springs are curved downwardly to engage a yoke member I which is adjustable to vary 15 the force exerted by the springs upon the spider of the chair. Any suitable means may be employed for adjusting the yoke member, the means shown including a bolt K which has a head k, and which extends 20 through a hole in the horizontal portion of the U-shaped member E and is bent so that the front end of the bolt extends forwardly in a substantially horizontal direction. The front end of the bolt extends between the 25 springs and through a hole in the yoke, and an adjusting nut L is secured on the front end of the bolt and is adapted to bear against the yoke I to move the same forwardly or rearwardly to vary the tension or force exerted by the springs. 30

The rear ends h' of the spring may be held in operative relation to the chair spider in any suitable or desired manner. In the construction shown for this purpose, the 40 two rivets d' of the spider are provided with heads at the lower ends of these rivets which have depressions or longitudinally extending notches M therein, as clearly indicated in Figs. 3, 6 and 7 into which the 45 forwardly extending ends h' of the springs may seat, and which holds these ends of the springs in their proper relation to the chair spider.

The springs H tend to swing the seat A 50 forwardly, and consequently stops are provided for limiting the swinging of the seat about its pivot, both forwardly due to the action of the springs, and rearwardly against the action of the springs. In the particular 55 construction shown for this purpose, the upwardly extending legs of the U-shaped spider supporting member E are provided at their upper ends with stop faces or edges N adapted to engage the connecting plate D 60 of the spider when the seat is swung to substantially horizontal position by the springs, as indicated in Fig. 2. The rearward swinging of the seat A about the pivot G is limited by means of edges or faces O, also formed 65 on the upper ends of the upwardly extending

legs of the U-shaped members E and arranged at an inclination to the faces N and adapted to engage the rear portions of the connecting plate D when the seat is swung to the limit of its rearward movement against 70 the action of the springs H. By means of this construction no additional expense is involved to provide the stop for limiting the movement of the chair seat, since the spider supporting member E itself forms the stops. 75 The upper ends of the U-shaped member E in addition to acting as stops, as described, also preferably bear against the sides of the downwardly extending flanges of the angle-shaped member C of the spider to hold the 80 spider in correct relation to the chair spindle B.

The chair iron described has the advantage of being unusually light in construction without any sacrifice of strength. The two 85 springs H disclosed in the drawings are of about one-third of the weight of the usual coil springs employed for the same purpose in constructions heretofore used, and furthermore, it has been found that by providing a coil spring of the kind shown, in which the coil itself is subjected to torsion, there is less chance for crystallization, and consequently the springs last longer. It will also 90 be noted that there is no relative movement or sliding movement between the parts of the springs engaging the spider when the chair seat is swung rearwardly, so that there is no tendency of the springs to squeak or to yield unevenly due to friction interposed 95 between the springs and the chair spider. 100

I claim as my invention:

1. The combination with a chair spider and a chair spindle, of a member mounted on the upper end of said spindle and on which said spider is pivotally supported, a spring engaging said member and said spider and having a coil which is subjected to torsion, one end of said spring extending rearwardly from said coil and bearing upwardly against said spider to resist the rearward swinging of the same and the other end of the spring extending forwardly from said coil, and means engaging said other end of said spring and said member for varying the tension of said spring. 105

2. The combination of a chair spider including a pair of flanged members having substantially horizontal flanges and substantially upright flanges, a supporting member for said spider having upwardly extending parts pivoted on said upright flanges, a spring for opposing the rearward swinging of said spider about said supporting member, a substantially horizontal stop face on said upwardly extending parts of said supporting member which is adapted to co-operate with a horizontally extending flange of said spider to limit the forward swinging 115 movement of said spider, and a rearwardly 120 125 130

inclined stop face on said upwardly extending parts which is adapted to engage a horizontally extending flange of said spider for limiting the rearward swinging movement 5 of said spider.

3. The combination of a chair spider including a pair of flanged members, which have substantially downwardly extending flanges and horizontally extending flanges, 10 a spider supporting member having a pair of upwardly extending arms arranged in proximity to said downwardly extending flanges to enable said flanges to hold said spider supporting member against lateral 15 displacement relatively to said spider and pivotally connected therewith, a spring for opposing the rearward swinging of said spider about said supporting member, and substantially horizontal and rearwardly inclined faces on the upper ends of said upwardly extending parts of said supporting member which are adapted to cooperate with the horizontally extending flanges of said flanged members to limit the forward and 20 rearward swinging movements respectively 25 of said spider about said pivot.

4. The combination of a chair spider having a pair of flanged members provided with substantially horizontal flanges and downwardly extending flanges, a substantially horizontal connecting plate secured to said horizontal flanges, a spider supporting member including upwardly extending parts which are pivoted on the downwardly extending flanges of said spider member, a spring for opposing the rearward swinging of said spider, and substantially horizontal and rearwardly inclined stop faces on the upper end of said upwardly extending parts which are adapted to engage said connecting plate to limit respectively the forward and rearward swinging movement of said spider about said pivot.

5. The combination with a chair spider including several parts secured together by a connecting device having a head provided with a groove extending across said head, means for pivotally supporting said spider, and a torsion spring connecting said means and said spider and adapted to bear on said connecting device and to extend into said groove to hold said spring in correct relation to said chair.

6. A chair including two parts, one of which is adapted to swing relatively to the other part, a torsion spring connecting said parts for opposing the swinging of one of said parts in one direction, and a rivet used in the construction of one of said parts and 50 which has a head provided in its end with a depression forming a seat for a part of said spring to hold said spring in correct relation to said parts.

7. The combination of a chair spider having two bars each provided with a substan-

tially horizontal flange and with a downwardly extending flange, a plate connecting said horizontal flanges, rivets extending through said plate and said flanges for securing said plate to said flanges, a spider supporting member to which said spider is pivotally secured, a torsion spring, the rear end of which is adapted to engage said spider and is held in operative relation to said spider by one of said rivets, and means for connecting the other end of said torsion spring to said spider supporting member. 70

8. The combination of a chair spider having two bars provided with substantially horizontal flanges and with downwardly extending flanges, a plate connecting the horizontal flanges of said bars, rivets securing said plate to said flanges, the lower heads of said rivets being provided with transverse depressions, a spider supporting member on which said spider is pivoted, and spring bars for opposing the rearward swinging of said spider, the rear ends of said bars entering into the depressions in said rivets for securing said bars in operative relation to said 90 spider. 80

9. The combination of a chair spider, a spider supporting member of substantially U-shaped cross section having upwardly extending legs to which said spider is pivoted, a torsion spring, one end of which engages said spider and the other end of which extends forwardly of said supporting member and oppositely to said first mentioned end of said spring, a bolt connected with the bottom of said U-shaped member and bent forwardly therefrom so that the front end of said bolt extends substantially at right angles to the other end of said spring, and a nut arranged on said bolt and adapted to engage said other end of said spring for adjusting the tension thereof. 95

10. In a chair iron the combination of a spider consisting of a pair of bars of angle shaped cross section the flanges of which are arranged substantially horizontally and vertically, a connecting plate secured to the horizontally arranged flanges of said angle bars, a spider supporting member of substantially U-shape, a pivot connecting the upper ends of said U-shaped member to the downwardly extending flanges of said angle bars, a pair of torsion springs having coils arranged about said pivot, one end of each of said springs engaging said spider and the other end of each spring extending forwardly of said U-shaped member, a threaded bolt secured to said U-shaped member and extending forwardly therefrom, and a nut on said bolt engaging the forwardly extending ends of said springs and adapted to vary the tension thereof. 110

11. In a chair iron the combination of a spider consisting of a pair of bars of angle-shaped cross section having their flanges ar-

ranged substantially horizontally and vertically, a connecting plate secured to said horizontally arranged flanges of said angle bars, a spider supporting member of substantially U-shape, a pivot connecting the upper ends of said U-shaped member with the downwardly extending flanges of said angle bars, a pair of torsion springs having coils arranged about said pivot, one end of each of said springs engaging said spider, a threaded bolt secured to said U-shaped member and extending forwardly therefrom, a

nut on said bolt engaging the other ends of said springs and adapted to vary the tension thereof, and a pair of rivets connecting said angle bars and said connecting plate and having transverse slots formed in the lower spaces thereof, the ends of said springs which engage the spider being adapted to enter into said slotted ends to position the ends of the springs relatively to said chair iron. 15 20

ROBERT K. DAWSON.
